CLAIM

The ornamental design for a venturi device, as shown and described.

DESCRIPTION

FIG. 1 is a front perspective view of one embodiment of a venturi device of our design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof; and,

FIG. 7 is a bottom view thereof.

The broken lines shown represent the portions of the venturi device that form no part of the claimed design.
